UNITED STATES PATENT OFFICE.

WILLIAM ZOLLER, OF ALLEGHENY CITY, PENNSYLVANIA.

CLASP FOR SUSPENDERS.

SPECIFICATION forming part of Letters Patent No. 373,793, dated November 22, 1887.

Application filed June 16, 1887. Serial No. 241,505. (No model.)

To all whom it may concern:

Be it known that I, WILLIAM ZOLLER, a citizen of the United States, residing at Allegheny City, in the county of Allegheny and State of Pennsylvania, have invented certain new and useful Improvements in Clasps for Suspenders; &c.; and I do declare the following to be a full, clear, and exact description of the invention, such as will enable others skilled in the art to which it appertains to make and use the same.

This invention relates to the construction of clasps for suspenders and other devices whenever it becomes desirable to grasp and hold a cord with great security, and is especially adapted for use on shirts of the class and character shown in the drawings.

In the accompanying drawings, Figure 1 is a front view of my improved shirt having suspender attachments. Fig. 2 is a view of part of the back of the shirt, also having a suspender attachment. Fig. 3 shows the shape of the blank of the clasp before it is bent into shape to form the attachment for the suspender-strap and button-hole tag. Fig. 4 is an edge view of the blank when its tongues are bent to form eyes and passed through the central eye in the blank. Fig. 5 shows the ends of the tongue bent outward. Fig. 6 is an edge view of the finished clasp. Fig. 7 is a vertical section through the clasp with the button-hole tag and part of a suspender attached to it.

For the purpose of securely and cheaply attaching the button-hole tags to the ends of

the suspenders I employ the following device: D' designates a blank which is struck out of sheet metal in the form represented by Fig. 3 of the annexed drawings. This consists of a central circular portion, d, two tongues, e e, 40 serrated at f f, and an oblong aperture, g.

I first bend the tongues e e and pass their ends through the aperture g, as shown by Fig. 4, forming eyes or loops i i for embracing and holding the bent end of the suspender-strap. 45 I then bend the ends of the tongues e e outward, as shown in Fig. 5. I then bend the ends of said tongues at the inner terminus of the serrations f f, as shown in Fig. 6. I then insert the end of a button-hole tag t between the 50 bent portions, and finally press the serrated ends firmly against such tag, whereby the serrations enter into and hold the tag with great security.

Having described my invention, what I claim 55 is—

1. For the purpose described, a clasp formed from a blank, D', and consisting of the eyes i i and serrated clasping portions e e, substantially as specified.

2. The within-described clasp-blank D', consisting of the central slotted portion, d, and the tongues e, having serrations f f, adapted for the purpose described.

In testimony whereof I affix my signature in 65 presence of two witnesses.

WILLIAM ZOLLER.
